Primary Examiner — Angela J Lee*Assistant Examiner* — Audris Park(74) *Attorney, Agent, or Firm* — Notaro, Michalos & Zaccaria P.C.(57) **CLAIM**

The ornamental design for a solar light, as shown and described.

DESCRIPTION

FIG. 1 is a top, front, left perspective view of a solar light showing my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

Throughout the drawings, broken lines denote boundaries that form no part of the design to be patented.
